(57) **CLAIM**

The ornamental design for a crusher jaw, as shown and described.

DESCRIPTION

FIG. 1 is a front, top, right perspective view of a crusher jaw showing my design therefor;
FIG. 2 is a bottom plan view thereof;
FIG. 3 is a top plan view thereof;
FIG. 4 is a front perspective view thereof;
FIG. 5 is a rear perspective view thereof;
FIG. 6 is a left side elevational view thereof;
FIG. 7 is a right side elevational view thereof;
FIG. 8 is a bottom, rear, right perspective view thereof;
FIG. 9 is a bottom, front, right perspective view thereof;
FIG. 10 is a top, rear, left perspective view thereof; and,
FIG. 11 is a top, front, right perspective view thereof.
The broken lines in the drawings depict unclaimed environmental subject matter.
